(57) **CLAIM**

The ornamental design for a vacuum control valve, as shown and described.

DESCRIPTION

FIG. 1 shows a front view of a vacuum control valve showing my new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof;

FIG. 7 shows a top, front and left side perspective view thereof; and,

FIG. 8 shows a top, rear and right side perspective view thereof.

In the drawings, the tubes are shown with breaks to indicate that no specific tube length is claimed.
